UNITED STATES PATENT OFFICE

2,386,531

BRASSIÈRE

Max Witkewer, Los Angeles, Calif.

Application September 27, 1943, Serial No. 503,927

3 Claims. (Cl. 2—42)

This invention relates to improvements in an article of women's wearing apparel, commonly termed a brassière, and more particularly it relates to a nursing type of brassière.

This brassière is particularly designed to produce a garment which forms a substantial support for the breasts both when used normally and during the nursing operation.

It is an object of my invention to provide a brassière of the character described of simple form and structure which may be readily adjusted for nursing and which retains its position on the body of the wearer and performs a maximum supporting function of both breasts at all times.

Other objects and advantages will appear hereinafter from the following descriptions and drawing. Referring to the drawing, which is for illustrative purposes only:

Fig. 1 is a perspective view of a brassière embodying a form of my invention as same appears on the wearer;

Fig. 2 is a view of the brassière shown in Fig. 1, laid out in a flat position with one of the breast pockets opened for nursing; and

Fig. 3 is an inside view of a portion of the brassière shown in the preceding figures.

Referring more particularly to the drawing, the brassière consists of two breast pockets generally indicated at 5. These breast pockets are each formed of two pieces of material, a front section or panel indicated at 6, connected to the side portion indicated at 7 by sewing along the medial line of the breast pocket as indicated at 8. The side portions 7 of the breast pockets which may be termed bands, extend around the side and back of the wearer and terminate in tabs indicated at 10, which may be made of webbing or elastic material, one of the tabs being provided with hooks indicated at 11, and the other with a series of eyelets indicated at 12, the eyelets being so arranged that an adjustment of the brassière to fit the body may be made by inserting the hooks in the proper eyelets.

13 indicates the shoulder straps, the rear end of each being secured to the back of the brassière by sewing or in any other suitable manner, as indicated at 14. The front end of each shoulder strap 13 is sewed or secured by any other suitable means to a ribbon or strip of material indicated at 16. One end of this ribbon is secured by sewing to the upper medial portion of the breast pocket and the other end is provided with an adjustment indicated at 17, and a loop indicated at 18, adapted to be engaged by hook 19 on the

upper end of a V-shaped central breast supporting member or panel indicated at 22 on the inside of the breast pockets. This supporting member is formed of two pieces of fabric indicated at 23 and 24, joined together on a medial line of the brassière by sewing as indicated at 25. The upper ends of these two pieces, 23 and 24, extend upwardly and outwardly over the adjoining breast pocket, and the sides of the pieces 23 and 24 are stitched or otherwise secured to the lower part of the breast pocket along the medial line of same as indicated at 26.

The panel 22 is of substantial size and in fact completes the front section of the brassière so that whether used normally or as a nursing brassière, it performs the function of supporting the breasts by a direct lifting action. When used as a nursing brassière the opening of the breast pockets does not interfere with the function of 20 the panel in performing its supporting function, in fact the opening of the pocket allows the breast to move outwardly from the body into normal nursing position.

The breast pockets are detachably secured 25 along the medial line of the brassière, one of the pockets being provided with a series of hooks, indicated at 30, engageable in a series of eyes or eyelets 31 on the opposite breast pocket and when engaged the breast pockets assume the position 30 shown in Fig. 1.

At the top of each breast pocket 1 is a loop 32 which engages a hook 33 on its associated shoulder strap. This connection, being on the medial line of the breast pocket, keeps the upper portion 35 of the breast pocket stretched over the breast of the wearer.

When it is desired to use the brassière for nursing, the hooks 30 are detached from the eyes 31 and the side of the brassière desired to fully 40 open is released by removing the loop 32 at the top of the breast pocket from the hook 33. When this is done the breast pocket as released assumes the position shown in Fig. 2. When the brassière is open, as just described, it is to be noted that the central or inner section 22 of the brassière remains in place forming a full support for the breast as when the breast pockets are closed.

In this case it is understood that while the breast pockets assist in supporting the breasts, 45 they are primarily in effect a covering for the breasts.

I claim as my invention:

1. In a brassière: a pair of breast pockets narrowing at the sides to form bands; means for 50 detachably securing the ends of the bands to-

gether; means for detachably securing the breast pockets together along the medial line of the front of the brassière; a pair of shoulder straps having their back ends secured to the breast pocket bands; a ribbon secured intermediate its ends to the front end of each shoulder strap, one end of the ribbon being attached to the upper portion of its associated breast pocket; a breast supporting member terminating upwardly in two divergent ends terminating at sides at and attached by stitching to the lower portion of the breast pockets; means for detachably securing the upper ends of the supporting member to the other ends of said ribbons.

2. In a brassière: a pair of breast pockets narrowing at the sides to form bands; means for detachably securing the ends of the bands together; means for detachably securing the breast pockets together along the medial line of the front of the brassière; a pair of shoulder straps having their back ends secured to the breast pocket bands; a ribbon secured intermediate its ends to the front end of each shoulder strap, one end of the ribbon being detachably secured to the upper portion of its associated breast pocket on 15

the medial line of the pocket; a V-shaped breast supporting member terminating upwardly in two outwardly curved divergent ends terminating at sides at and attached by stitching to the lower portion of the breast pockets on the medial line of the breast pockets; means for detachably securing the upper ends of the supporting member to the other ends of said ribbons.

3. In a brassière having breast pockets detachably secured together and terminating at their sides in bands detachably secured at the back of the brassière; a V-shaped panel at the front of the brassière having outwardly diverging lower portions secured to the respective lower outer portions of the breast pockets only along the medial line of the breast pockets; shoulder straps attached at the back of the brassière to the said bands; a ribbon attached at one end to the brassière and connected intermediate its length to each shoulder strap at the front end of the straps; and means for adjustably attaching the other ends of the ribbons to the divergent upper ends of the V-shaped panel.

MAX WITKOWER.
